SELECTIVE OXIDATION OF DIHYDROXY STEROIDS

Robert E. Jones, Rahway, N. J., assignor to Merck & Co., Inc., Rahway, N. J., a corporation of New Jersey

No Drawing. Application September 16, 1950,
Serial No. 185,320

9 Claims. (Cl. 260—397.4)

1

This invention is concerned generally with selective oxidation of hydroxyl groupings in steroid compounds. More particularly, it relates to the process of selectively oxidizing the 3-hydroxyl grouping of the steroid compound Δ^{17} -3,21-dihydroxy-11-keto-20-cyano-pregnene without affecting the hydroxy substituent in the 21-position, thereby forming Δ^{17} -3,11-diketo-20-cyano-21-hydroxy-pregnene. The latter compound is valuable as an intermediate in the synthetic manufacture of cortisone (Δ^4 -3,11,20-triketo-17,21-dihydroxy-pregnene).

The selective oxidation reaction, subject of the present invention, may be chemically represented as follows:

Heretofore, it was not considered possible to selectively oxidize a secondary alcohol grouping in the presence of a primary alcohol grouping as is required to achieve the reaction described hereinabove. Attempts have been made to accomplish this transformation by subjecting the Δ^{17} -3,21-dihydroxy-11-keto-20-cyano-pregnene to a partial acetylation reaction whereby the primary 21-hydroxy substituent is preferentially acetylated while leaving the secondary 3-hydroxy radical unchanged. The resulting Δ^{17} -3-hydroxy-11-keto-20-cyano-21-acetoxy-pregnene may then be oxidized to the corresponding 3-keto-derivative without affecting the 21-acetoxy substituent. Alternatively, the Δ^{17} -3-hydroxy-11-keto-20-cyano-21-acetoxy-pregnene may be reacted with osmium tetroxide and the resulting 17,20-oximate ester of 3,17,20-trihydroxy-11-keto-20-cyano-21-acetoxy-pregnane may then be oxidized to the corresponding 3-keto derivative utilizing chromic acid. The overall yield obtained according to the foregoing procedures, however, has ordinarily been in the neighborhood of 50% due in part to the fact that the yield of monoacetyl derivative, obtained utilizing the partial acetylation reaction, is ordinarily less than about 85% of theory.

It is now discovered, however, that the 3-hydroxy-grouping in Δ^{17} -3,21-dihydroxy-11-keto-

2

20-cyano-pregnene can be selectively oxidized to a 3-keto radical without affecting the hydroxy substituent in the 21-position by reacting said Δ^{17} -3,21-dihydroxy-11-keto-20-cyano-pregnene with an oxidizing agent selected from the class which consists of N-bromoacetamide and N-bromosuccinimide. This discovery is indeed surprising in view of the fact that N-bromoacetamide has previously been used in place of hypobromous acid (HOBr) for the addition of hydroxyl and bromine groupings to a carbon to carbon double bond. Since Δ^{17} -3,21-dihydroxy-11-keto-20-cyano-pregnene possesses an unsaturated carbon to carbon linkage between the 17 and 20-carbon atoms, it might have been expected that addition of hypobromous acid to the double bond between the 17 and 20-carbon atoms of the Δ^{17} -3,21-dihydroxy-11-keto-20-cyano-pregnene would have occurred.

In carrying out my improved process, the Δ^{17} -3,21-dihydroxy-11-keto-20-cyano-pregnene is dissolved in an organic solvent such as pyridine, tertiary butyl alcohol, methanol, and the like, and the oxidizing agent is added to the solution. As the oxidizing agent, it is ordinarily preferred to employ N-bromoacetamide, N-bromosuccinimide, and the like. The amount of oxidizing agent employed in the oxidation reaction may vary from 1.5 to 3 moles per mole of Δ^{17} -3,21-dihydroxy-11-keto-20-cyano-pregnene. It is ordinarily preferred to utilize approximately 2.75 moles of oxidizing agent per mole of 3,21-dihydroxy-pregnene starting material.

The preferred solvent for carrying out the reaction is methanol, and the addition of a small amount of pyridine to the reaction mixture appears to be advantageous. The oxidation is ordinarily carried out at a temperature between about 18 and 40°C. and for a period of about 6 to 30 hours. The optimum time and temperature for the reaction are respectively 6 to 8 hours and 25°C. The preferred pH range is between 6 and 7, although the reaction can be carried out if desired under more acid conditions or slightly more alkaline conditions than the preferred range. In this connection, it should be noted that at a pH greater than 8, the selectivity of the oxidation is lost, while at an acid pH less than about 2, bromination in the 4-position occurs.

It is also desired to point out that a certain amount of bromination occurs during the reaction even under the preferred conditions of pH, with the result that the Δ^{17} -3,11-diketo-20-cyano-21-hydroxy-pregnene compound is contaminated with bromine. In order to remove

this bromine, which is usually present in amounts of 1 to 2%, it has been found advantageous to treat the crude Δ^{17} -3,11-diketo-20-cyano-21-hydroxy-pregnene with zinc and acetic acid whereby the bromine is completely removed. The treatment with zinc is preferably carried out utilizing zinc dust and glacial acetic acid at a temperature of approximately 40° C. Instead of treating the crude (brominated) Δ^{17} -3,11-diketo-20-cyano-21-hydroxy-pregnene with zinc, it has been found advantageous to react this compound with an acylating agent such as acetic anhydride and pyridine to produce the corresponding Δ^{17} -3,11-diketo-20-cyano-21-acetoxy-pregnene. This 21-acetate can then be debrominated by reaction with zinc dust and acetic acid to give pure Δ^{17} -3,11-diketo-20-cyano-21-acetoxy-pregnene.

Alternatively, it has been found possible to minimize the contamination of the 3-ketopregnene product by brominated impurities by careful control of the reaction conditions. This is accomplished by titrating aliquots of the reaction mixture at intervals during the oxidation period utilizing as the titrating agent a standard thiosulfate solution thereby measuring the amount of oxidizing agent which is unconsumed (the oxidizing agent being usually present in excess). When the thiosulfate titration indicates that no more N-bromoacetamide or N-bromosuccinimide is being consumed, which indicates the completion of the reaction (ordinarily complete at the end of about 8 to 12 hours), allyl alcohol is added to react with any excess N-bromoacetamide or with any free N-bromosuccinimide which may be present. The latter procedure has been found to result in the production of a substantially pure crystalline product. It has also been found that bromination of the 3-ketone product can be minimized by conducting the oxidation reaction in the absence of light, with strict temperature control (25° C.) and by maintaining close adjustment of the pH (within the range of 6 to 7) as pointed out above. It is important to add allyl alcohol or other unsaturated compound prior to working up the reaction mixture since this treatment also minimizes bromination of the 3-ketone.

The following examples illustrate methods of carrying out the present invention but it is to be understood that these examples are given by way of illustration and not of limitation.

Example 1

16.75 grams (0.047 mole) of Δ^{17} -3,21-dihydroxy-11-keto-20-cyano-pregnene was dissolved in 37 cc. of pyridine, 25 cc. of water was added to the resulting solution with swirling, and 16.34 grams (0.11 mole) of N-bromoacetamide (92% pure) was then added to the resulting solution. A few minutes after the addition of the N-bromoacetamide the color of the solution turned to deep orange. The temperature of the reaction mixture was maintained within the range of 20-25° C. for a period of 2½ hours. The reaction mixture was then allowed to stand at room temperature overnight, at the end of which time the mixture was very dark, and profuse crystallization had occurred. The crystalline mixture was filtered and the crystalline product thus recovered was slurried with water and then given two additional displacement washes. The resulting solid product was dried to constant weight to produce 11.20 grams of Δ^{17} -3,11-diketo-20-cyano-21-hydroxy-pregnene (M. P. 221-225°

C.); yield 67.0% of theory. (This product contained much brominated impurities as shown by blackening and bubbling on melting.) The mixed melting point of this crude product with 5 an authentic sample of Δ^{17} -3,11-diketo-20-cyano-21-hydroxy-pregnene of M. P. 248-254° C. was 226-230° C.

The product was more positively identified by acetylation followed by purification of the resulting Δ^{17} -3,11-diketo-20-cyano-21-acetoxy-pregnene as follows: 2 grams of crude Δ^{17} -3,11-diketo-20-cyano-21-hydroxy-pregnene was dissolved in 5.00 cc. of pyridine and the solution was warmed to 55° C. 5 cc. of acetic anhydride 15 was added to the dark brown solution and the resulting solution was maintained at 55° C. for a period of 10 minutes. The pyridine solution was poured (with stirring) into 250 cc. of water. The resulting mixture was stirred for a period 20 of 30 minutes to decompose excess acetic anhydride and the precipitated material was recovered by filtration. The product was washed with three 25 cc. portions of water and dried to produce 2.2 grams of crude acetate, which was 25 then dissolved in 8 cc. of benzene. The benzene solution was decolorized by treatment with about 0.25 gram of activated charcoal (Darco G-60). The charcoal was removed by filtration and washed with 4 cc. of benzene. Upon cooling the 30 resulting solution, crystallization commenced and was brought to completion by the addition of about 2 volumes of petroleum ether and 2 volumes of ethyl ether. The crystalline material which precipitated was filtered and dried 35 to produce 1.2 grams of substantially pure Δ^{17} -3,11-diketo-20-cyano-21-acetoxy-pregnene; M. P. 194.2-195.2° C.; mixed M. P. with an authentic sample of Δ^{17} -3,11-diketo-20-cyano-21-acetoxy-pregnene was 193-195° C.

Example 2

Eighteen grams of Δ^{17} -3,21-dihydroxy-11-keto-20-cyano-pregnene were dissolved in 120 cc. of 45 tertiary butanol. To the resulting solution was then added 9.75 cc. of pyridine, 6.00 cc. of water and 16.90 grams of (90% pure) N-bromo-acetamide. The mixture turned orange colored after a few minutes and was maintained at a temperature of 20-25° C. overnight. Crystallization was 50 apparent after 2 to 3 hours and, at the end of 15 hours reaction time, crystallization of the product was brought to completion by the addition of an excess of water (about 3 volumes). The precipitated material was recovered by filtration, washed with three 25 cc. portions of water and dried to constant weight in a 50° C. drying oven to produce 18.69 grams of crude Δ^{17} -3,11-diketo-20-cyano-21-hydroxy-pregnene; yield 60 about 99% of theory.

18.69 grams of said crude Δ^{17} -3,11-diketo-20-cyano-21-hydroxy-pregnene was dissolved in 45 cc. of pyridine, and 15 cc. of acetic anhydride was added to the resulting solution while maintaining the temperature within the range of 45-55° C. The final mixture was heated for a period of 5 minutes at a temperature of 45-55° C., and the crude acetate was isolated by mixing the reaction mixture with 5 volumes of ice water, followed by stirring for a period of 1-2 hours. The precipitated material was recovered by filtration, washed and dried to produce 17.31 grams of crude (partially brominated) Δ^{17} -3,11-diketo-20-cyano-21-acetoxy-pregnene; M. P. 186-188° 75 C.; yield 83% theory.

17.3 grams of crude Δ^{17} -3,11-diketo-20-cyano-21-acetoxy-pregnene was dissolved in 115 cc. of glacial acetic acid by warming the solution to a temperature of approximately 40° C. The resulting solution was vigorously agitated while three 800 mg. portions of zinc dust were added thereto at 45 minute intervals, while maintaining the temperature of the reaction mixture at approximately 40° C. Two additional 1200 mg. portions of zinc dust were added to the resulting mixture at intervals of 30 minutes each. 500 mg. of activated charcoal (Darco G-60) was added together with the last portion of zinc dust, the reaction solution was filtered hot (temperature approximately 40° C.) and the crystallization of the product contained in the filtered solution was induced by a slow addition of three volumes of water. The precipitated material was recovered by filtration, washed free of acid and dried at a temperature of 50° C. to produce 16.01 grams of substantially pure (debrominated) Δ^{17} - 3,11-diketo-20-cyano-21-acetoxy-pregnene; M. P. 193.7-194.6° C.; yield approximately 79.6% of theory.

Example 3

Six grams of Δ^{17} -3,21-dihydroxy-11-keto-20-cyano-pregnene was dissolved in a mixture of 50 cc. of methanol and 9 cc. of pyridine by warming the mixture to approximately 40-50° C. Two cc. of water and 5.53 grams of N-bromoacetamide (98.5% pure) was added to the warm solution thus obtained, and, after 1 hour, a clear orange solution resulted. The resulting mixture was allowed to stand for a period of 3½ hours, at the end of which time 20 cc. of water was added to initiate crystallization whereupon the mixture was stirred for a period of 1 hour. An additional 125 cc. of water was added portionwise over a 1 hour period to the resulting mixture whereupon the remaining product in the solution crystallized and was recovered by filtration. The yellowish-colored crystals thus obtained were washed with water and dried at room temperature to produce 5.74 grams of crude (partially brominated) Δ^{17} - 3,11-diketo-20-cyano-21-hydroxy-pregnene.

The crude material, prepared as described in the preceding paragraph, was reacted with zinc dust in acetic acid solution utilizing the reaction conditions set forth in Example 2 to produce 4.46 grams of purified Δ^{17} -3,11-diketo-20-cyano-21-hydroxy-pregnene; M. P. 255.8-259° C.; yield approximately 74.3% of theory.

Example 4

6550 grams of acetamide was dissolved in 6550 cc. of water. 8850 grams of technical grade bromine was cautiously mixed with the acetamide solution, and the resulting mixture was cooled to 15° C. Meanwhile 7285 grams of 85% aqueous potassium hydroxide solution was mixed with 7230 cc. of water and the resulting solution was cooled to 0-5° C. This caustic solution was then added portionwise over a 2½ to 3 hour period to the cold bromine-acetamide mixture while maintaining the temperature of the mixture within the range of 10-15° C.

The resulting slurry of N-bromoacetamide was stirred for ½ hour to complete the reaction and 37.9 liters of methanol was added to effect complete solution of the product and to cause much of the undesired potassium bromide to crystallize. The resulting slurry was stirred for an additional ½ hour period and was then filtered. The deep orange solution was weighed, titrated to

determine its oxidation equivalent and the specific gravity determined. One cubic centimeter of the solution (sp. g. 1.07) was found to contain 138 mg. of N-bromoacetamide, which showed that 41.5 kilograms of the N-bromoacetamide solution would be required for the oxidation of one hydroxyl in five kilograms of Δ^{17} -3,21-dihydroxy-11-keto-20-cyano-pregnene.

5000 grams (14 moles) of Δ^{17} -3,21-dihydroxy-11-keto-20-cyano-pregnene, 69.3 liters of methanol and 1045 cc. of pyridine were placed in a 100 gallon vessel and the resulting mixture was cooled to 18° C. 41.5 kilograms (38.6 moles) of the N-bromoacetamide solution prepared hereinabove was added portionwise while vigorously agitating the reaction mixture. The temperature of the reaction mixture was maintained within the range of 18-20° C. for a period of 22½ hours, and during this time light was excluded from the mixture in the reaction vessel. At the end of the reaction period 1800 cc. of allyl alcohol was added to the reaction mixture to destroy the excess oxidizing agent. 1020 cc. of concentrated hydrochloric acid was then added to the resulting solution, and the solution was transferred to a 150 gallon vessel and cooled to 5-10° C. 210.8 liters of water was added portionwise to the cooled mixture over a 45 minute period and the crystalline slurry which resulted was stirred for a period of 3 hours while maintaining the temperature within the range of 5-10° C. The slurry was then filtered and the filter cake was washed thoroughly with four 10 gallon portions of water, and dried for a period of 3 days at a temperature of 50° C. to produce 4700 grams of Δ^{17} - 3,11-diketo-20-cyano-21-hydroxy-pregnene, M. P. 245.7° C.; yield 94.5% of theory.

The Δ^{17} - 3,11 - diketo - 20 - cyano - 21 - hydroxy-pregnene thus obtained was acetylated utilizing the same acetylation procedure described in Example 1, and the acylated product debrominated by reaction with zinc dust and glacial acetic acid utilizing the reaction conditions set forth in Example 2 thereby producing substantially pure Δ^{17} - 3,11 - diketo - 20 - cyano - 21-acetoxy-pregnene; M. P. 194-195° C.; yield approximately 86% of theory.

Example 5

50 Two grams of Δ^{17} -3,21-dihydroxy-11-keto-20-cyano-pregnene (0.0056 mole) were suspended in 25 cc. of methyl alcohol containing 1.1 cc. of pyridine and 0.67 cc. of water. 2 grams of N-bromosuccinimide (0.0112 mole) was added to this solution with stirring in the absence of light, and the resulting mixture was stirred at room temperature for a period of 20 hours. 0.6 cc. of allyl alcohol was then added to the solution, followed by a solution containing 1.2 cc. of concentrated hydrochloric acid mixed with 1.2 cc. of water. 75 cc. of water was then added portionwise to the resulting mixture whereupon the 3-keto compound crystallized, and was recovered by filtration and dried to produce 2.01 grams of Δ^{17} - 3,11 - diketo - 20 - cyano - 21 - hydroxy-pregnene; M. P. 219.5-222.5° C.

This product was then dissolved in chloroform and subjected to chromatographic purification utilizing a column of 20 grams of acid-washed alumina thereby producing 1.76 grams of substantially pure Δ^{17} -3,11-diketo-20-cyano-21-hydroxy-pregnene; M. P. 248.5-250.6° C.; yield 88.4% of theory.

Various changes and modifications may be made in carrying out the present invention with-

out departing from the spirit and scope thereof. Insofar as these changes and modifications are within the purview of the annexed claims, they are to be considered as part of my invention.

I claim:

1. The process of selectively oxidizing the 3-hydroxy grouping in Δ^{17} -3,21-dihydroxy-11-keto-20-cyano-pregnene without affecting the hydroxy substituent in the 21-position which comprises reacting said Δ^{17} -3,21-dihydroxy-11-keto-20-cyano-pregnene with an oxidizing agent selected from the class which consists of N-bromoacetamide and N-bromosuccinimide.
2. The process which comprises reacting Δ^{17} -3,21-dihydroxy-11-keto-20-cyano-pregnene with N-bromoacetamide to produce Δ^{17} -3,11-diketo-20-cyano-21-hydroxy-pregnene.
3. The process which comprises reacting Δ^{17} -3,21-dihydroxy-11-keto-20-cyano-pregnene with N-bromosuccinimide to produce Δ^{17} -3,11-diketo-20-cyano-21-hydroxy-pregnene.
4. The process which comprises reacting Δ^{17} -3,21-dihydroxy-11-keto-20-cyano-pregnene with N-bromoacetamide in methanol to produce Δ^{17} -3,11-diketo-20-cyano-21-hydroxy-pregnene.
5. The process which comprises reacting Δ^{17} -3,21-dihydroxy-11-keto-20-cyano-pregnene with N-bromoacetamide in tertiary butanol to produce Δ^{17} -3,11-diketo-20-cyano-21-hydroxy-pregnene.
6. The process which comprises reacting Δ^{17} -3,21-dihydroxy-11-keto-20-cyano-pregnene with N-bromoacetamide in pyridine to produce Δ^{17} -3,11-diketo-20-cyano-21-hydroxy-pregnene.
7. The process which comprises reacting Δ^{17} -3,21-dihydroxy-11-keto-20-cyano-pregnene with N-bromoacetamide, said reaction be-

ing carried out in solution in methanol in the presence of pyridine, thereby producing Δ^{17} -3,11-diketo-20-cyano-21-hydroxy-pregnene.

8. The process for selectively oxidizing the 3-hydroxy grouping in Δ^{17} -3,21-dihydroxy-11-keto-20-cyano-pregnene without affecting the hydroxy substituent in the 21-position, which comprises reacting approximately 1 molecular equivalent of said Δ^{17} -3,21-dihydroxy-11-keto-20-cyano-pregnene with approximately 2.75 molecular equivalents of an oxidizing agent selected from the class which consists of N-bromoacetamide and N-bromosuccinimide, said reaction being carried out at a temperature of about 25° C. for a period of 6 to 8 hours in an organic solvent selected from the class which consists of pyridine, tertiary butyl alcohol and methanol, the pH of said solution being adjusted within the range of 6 to 7.
9. The process of producing Δ^{17} -3,11-diketo-20-cyano-21-hydroxy-pregnene substantially free of brominated impurities which comprises reacting together, in solution in an organic solvent selected from the class which consists of pyridine, tertiary butyl alcohol and methanol, Δ^{17} -3,21-dihydroxy-11-keto-20-cyano-pregnene and an oxidizing agent selected from the class which consists of N-bromoacetamide and N-bromosuccinimide thereby producing crude Δ^{17} -3,11-diketo-20-cyano-21-hydroxy-pregnene contaminated with brominated impurities, and reacting said crude Δ^{17} -3,11-diketo-20-cyano-21-hydroxy-pregnene with zinc and acetic acid.
